(57) **CLAIM**

The ornamental design for a stringed instrument plectrum, as shown and described.

DESCRIPTION

FIG. 1 is a perspective view of a stringed instrument plectrum of my new design;

FIG. 2 is a top plan view of the stringed instrument plectrum;

FIG. 3 is a bottom plan view of the stringed instrument plectrum;

FIG. 4 is a front elevation view of the stringed instrument plectrum;

FIG. 5 is a back elevation view of the stringed instrument plectrum;

FIG. 6 is a right elevation view of the stringed instrument plectrum; and,

FIG. 7 is a left elevation view of the stringed instrument plectrum.

FIGS. 1 through 7 represent a design for a stringed instrument plectrum, such as a guitar pick, a banjo pick, or a pick for any stringed instrument.

1 Claim, 1 Drawing Sheet
